Primary Examiner—Philip Hyder*Assistant Examiner*—Cynthia Underwood(74) *Attorney, Agent, or Firm*—Hahn Loeser & Parks LLP(57) **CLAIM**

The ornamental design for a travel mug with twist closure lid, as shown and described.

DESCRIPTION

FIG. 1 is a perspective view of a travel mug with twist closure lid.

FIG. 2 is a right side view of the travel mug with twist closure lid illustrated in FIG. 1, the left side view being a mirror image thereof; and,

FIG. 3 is a top view of the travel mug with twist closure lid illustrated in FIG. 1.

The broken lines shown in FIGS. 1 and 3 are for illustrative purposes only and form no part of the claimed invention.
